(57) **CLAIM**

The ornamental design for an elevator wall, as shown and described.

DESCRIPTION

The FIGURE is a front view of an elevator wall according to our new design.

The broken-lines illustrate environmental structure and form no part of the claimed design. In particular, the broken lines showing the side, top and bottom walls of the elevator cab are flat and unornamented.

The elevator wall is also flat, featuring a decorative pattern depicted in The FIGURE.
